(57) **CLAIM**

I claim the ornamental design for a windshield wiper and adapter, as shown and described.

DESCRIPTION

FIG. 1 is a perspective view of the windshield wiper and adapter in which the adapter is in the closed position according to a first embodiment of the disclosure;

FIG. 2 is a right side view thereof;

FIG. 3 is a top side view thereof;

FIG. 4 is a bottom side view thereof;

FIG. 5 is a rear side view thereof;

FIG. 6 is a front side view thereof;

FIG. 7 is a left side perspective view thereof;

FIG. 8 is a perspective view of the windshield wiper and adapter in which the adapter is in the open position according to a second embodiment of the disclosure;

FIG. 9 is a right side view thereof;

FIG. 10 is a top side view thereof;

FIG. 11 is a bottom side view thereof;

FIG. 12 is a front side view thereof;

FIG. 13 is a rear side view thereof; and,

FIG. 14 is a left side perspective view thereof.
